(57) **CLAIM**

The ornamental design for a soil sensor as shown and described.

DESCRIPTION

FIG. 1 is a perspective view of a soil sensor.

FIG. 2 is a top view of the soil sensor of FIG. 1.

FIG. 3 is a front view of the soil sensor of FIG. 1.

FIG. 4 is a right side view of the soil sensor of FIG. 1.

FIG. 5 is a rear view of the soil sensor of FIG. 1.

FIG. 6 is a left side view of the soil sensor of FIG. 1; and,

FIG. 7 is a bottom view of the soil sensor of FIG. 1.

The broken lines are included for the purpose of illustrating portions of the soil sensor and form no part of the claimed design.
